UNITED STATES PATENT OFFICE.

FRANCIS MILTON WILDER, OF NEW YORK, N. Y., ASSIGNOR, BY MESNE ASSIGNMENTS, TO THE CONSOLIDATED COUPLING COMPANY, OF NEW JERSEY.

CAR-COUPLING.

SPECIFICATION forming part of Letters Patent No. 394,745, dated December 18, 1888.

Application filed July 19, 1887. Serial No. 244,685. (No model.)

To all whom it may concern:

Be it known that I, FRANCIS MILTON WILDER, of the city, county, and State of New York, have invented certain new and useful 5 Improvements in Car-Couplings, of which the following is a specification.

My invention relates to the method and means employed for coupling cars provided with dissimilar couplings and of varying 10 height. It is a matter of frequent occurrence that cars provided with dissimilar couplings have to be connected together to form a train, and it is essential that some means be provided not only to couple them, but to take up 15 the slack between the cars. Again, different classes of cars have frequently to be coupled—as, for instance, a short car with fixed axles with a long car with swinging trucks. Where two such cars are brought together, if the 20 draw-bar occupies a fixed position relatively to the body of the car, as is commonly the case in this country—that is to say, has no lateral motion—it will be found that in rounding a curve the long car will throw the small 25 car off the track. To overcome this tendency and to provide a suitable coupling I have devised the mechanism which I will now proceed to describe.

In the drawings, Figure 1 is a plan view 30 showing an American railway-car coupled to a railway-carriage of English construction. This figure illustrates more particularly the arrangement of the draw-head relatively to the body of the car, as also the relation of the 35 buffing-surfaces to each other. Fig. 2 is an end view from the front of the platform of an American car, and shows the arrangement of the draw-head and buffing-surfaces. Fig. 3 is a longitudinal section of the car-bodies, taken 40 on the line X X of Fig. 1, and shows the coupling-links employed.

In the drawings, A represents the framework of an American car, and B a draw-head or coupling device of the class known as "vertical plain couplers." The draw-head B is secured between the beams A and A' by means of the angle-iron stops C C, bolted to the beams. The end of the draw-head is provided with

the screw D, and E F are two follower-plates, between which is located a helical or other 50 suitable spring, G.

H is a nut on the screw D, by which the tension of the spring G may be adjusted.

I are leaf-springs secured to the beams A and A' and bearing at their outer ends upon 55 the sides of the draw-head, thereby tending to keep the draw-head in a central position.

The draw-head B is held in the saddle J, Fig. 2, which is made sufficiently wide to allow a certain amount of lateral play of the 60 draw-head relatively to the axial line of the car.

K K are platform-buffers, such as are commonly employed with couplers of this class.

L are plates adapted to be attached to a 65 platform, M, of an American car, and on which the buffers N—such as are usually employed on foreign-made cars—bear and play. In order to prevent the buffers N from rising above the platform M of an American car, the buffer- 70 plate L is provided with a top or extended portion, O. (Shown in Fig. 3.)

In Fig. 3 the coupling-hook P of the foreign cars is shown, and over the hook the link Q, bifurcated to lay over and in the orifice of 75 the coupler of the American car.

Referring to the drawings, Fig. 1, the draw-head is shown in dotted line, illustrating that when cars coupled as shown take a curve the draw-head has sufficient capacity for lateral displacement to bring the line of traction in the axial line of the shortest car. As a consequence, the coupling will always remain intact, and there will be no tendency of the short car to leave the track. 85

I do not limit myself to these specific mechanisms shown and described, as it is obvious that many mechanical changes may be made therein without departing from the intent of my invention. 90

I do not broadly claim an oscillating draw-bar, as such draw-bars have been made in which the end of the bar has a pivotal bearing or point of connection around which it may oscillate. In my device, on the other 95 hand, there is no such point of support for

the end of the bar, it being held in the required position by means of the spring and plates.

I claim as my invention—

- 5 1. The combination, with a car-platform and an oscillating draw-head, of the buffer-plates L L, provided with the extended tops O on each side of said platform, substantially as described.
- 10 2. The combination, with a draw-head and

a car-platform, of the buffer-plates L L, provided with the extended tops O on each side of said platform, substantially as described.

In witness whereof I have hereunto set my hand this 18th day of July, 1887.

FRANCIS MILTON WILDER.
